UNITED STATES PATENT OFFICE.

HENRY NORMAN LEASK, OF WALLASEY, ENGLAND.

REFUSE-DESTRUCTOR FURNACE.

1,307,909.

Specification of Letters Patent. Patented June 24, 1919.

Application filed February 11, 1916. Serial No. 77,728.

To all whom it may concern:

Be it known that I, HENRY NORMAN LEASK, a subject of the King of Great Britain, residing in Wallasey, England, have invented certain new and useful Improvements in Refuse-Destructor Furnaces, of which the following is a specification.

One of the greatest difficulties in connection with refuse destructors is the question 10 of handling of the clinker and ash formed as a result of the combustion. The withdrawal of this clinker and ash, especially where the refuse is of low calorific value, disengages large quantities of dust, which is 15 not only objectionable in itself but is deleterious to any mechanical portions of the plant and injurious to the men operating it.

Where the refuse is of higher calorific value and larger masses of clinker are formed, the 20 clinker, owing to the size of these masses, is difficult and expensive to remove and transport.

In an ordinary furnace, the quality of the fuel consumed or burnt is regular, and the 25 amount of residue produced by the consumption is very small in proportion to the amount of fuel burnt, and is also a more or less regular quantity, so that there is little difficulty in removing such residue while the 30 furnace is maintained continuously burning. In a refuse destructor, however, the amount of residue left after the burning of the fuel is comparatively large, being anywhere from 25 to 50 per cent., or even more, 35 in weight, of the weight of the original refuse introduced into the furnace. The quality of the refuse to be consumed also generally varies to a very great extent. The essential difference, therefore, between an ordinary furnace and a refuse destructor, and 40 the particular difficulty in dealing with refuse in a destructor, lie in the means for removing the residue after the refuse has been burnt. In general, it has been found

45 that the best course is to charge the refuse destructor and to burn the refuse, and to remove the residue after the fire has been burnt out. It is common to burn several charges of refuse one after the other till the 50 grate is full of clinker, when the whole of the contents of the grate is withdrawn and the fire is then started over again, so that in a refuse destructor the general practice is, instead of having a continuous fire, as in an 55 ordinary furnace, to have an intermittent

fire; and to produce a continuous result from such a destructor, it is usual to arrange a plurality of grates side by side in one structure, so that, while the grates in turn may be out of action, the heat produced from the 60 whole combustion may be more or less continuous.

The object of the present invention is to devise a simple means by which the block or mass of clinker produced in a refuse destructor may be readily and simply handled. At present, the difficulty of handling the clinker from a refuse destructor is very great. It has either to be broken up in the grate before it is withdrawn, or has to be withdrawn 70 in one mass and handled, according to circumstances.

According to the present invention, an improved refuse destructor is provided, having a water chamber with or without a spill-way arranged beneath the furnace into which the clinker can be deposited in a mass directly from the combustion zone, such submersion of the clinker preventing the dispersal of dust and at the same time breaking up or granulating the clinker so that it 75 can be easily handled or transported.

The invention will be fully described with reference to the accompanying drawings which illustrate diagrammatically several 80 embodiments of the invention. Throughout the specification similar parts are indicated by similar reference letters but different indices are employed for the different modifications and where, in the description of a 85 figure such references are not specifically referred to the parts in question are similar to those in previously described figures.

In said drawings:—

Figure 1 is a vertical sectional view of 90 one form of the invention.

Fig. 2 is a view generally similar to Fig. 1, but showing a modified form of water pit or tank.

Fig. 3 is a fragmental sectional view, 100 showing a further modified form of water pit, and also showing, in dotted lines, a grab for removing the granulated clinker.

Fig. 4 is a sectional view of a still further modification, showing the use of hydraulic 105 plungers for lowering the hearth, and for removing the clinker therefrom when lowered.

Fig. 5 is a sectional view showing the use of a hinged hearth.

Fig. 6 is a sectional view showing the use of a pivoted hearth which is controlled by a hydraulic plunger.

In any of the arrangements of destructor shown in the drawings the combustion zone (generically indicated by A) of the furnace is formed with metal walls a , which may be of any suitable shape or construction according to circumstances and are arranged so as to be maintained relatively cool by means of water, steam or air, or any combination of them. The combustion zone may be round, oval, square or other shape, and its walls may be cooled in any way deemed advisable; for example it may be formed with a jacket a' through which air, steam or water is circulated in any suitable manner.

The forms of destructor furnace here shown, while being particularly applicable for refuse of higher calorific value, which on combustion produces large masses of clinker, may also be employed for refuse of lower calorific value which produces a larger proportion of ash and little or no clinker. In all of these arrangements a combustion zone, generically indicated by A, such as above described may be employed and underneath the zone A is arranged a movable hearth or door (generically indicated by H) adapted to be removed or lowered when a fire is burnt out, to drop or submerge the clinker into the pit or tank (generically indicated by B) of water arranged beneath it, which is made of sufficient size to wholly submerge the clinker. The hot clinker on being immersed granulates or breaks up into pieces which can be readily handled or transported, and can be removed from the bottom of the pit or tank B in any suitable manner, either mechanically or by hand, and the ash is quenched so that it will not fly about.

In the arrangement shown in Fig. 1, a combustion zone A' such as above described and having substantially vertical walls a , is built or supported in any suitable manner in the furnace brickwork, and arranged underneath the combustion zone is a pit or tank B' adapted to be filled with water, either so that the water rises above the bottom of the walls of the combustion zone A' and forms a water seal to prevent the escape of air or not, air for combustion being introduced into the zone through tuyers or openings c' in its walls from an air duct C'.

Beneath the combustion zone A' is provided a hearth H' adapted normally to close it at the bottom but capable of being slid or moved to one side to allow the clinker in the grate to drop into the tank B' when the charge is burnt out.

Where the refuse to be destroyed contains much moisture a drying hearth D' may be arranged over the combustion zone A' on to which the refuse is dropped and upon which

it is dried by both radiant heat and convection from the hot gases of combustion, after which the dried refuse is raked or pushed into the combustion zone or grate in large or small quantities. Except in the case of wet refuse, however, such a drying hearth is not necessary.

Where a drying hearth is not employed, the refuse may be fed directly to the combustion zone, or it may first be fed on to the shelf E' from which it may be pushed into the combustion zone A'.

In operation, the refuse is fed into the combustion zone in any suitable manner, as above described, either in one or several operations and either by hand or mechanically and, as combustion takes place, clinker is formed, and when the fire is burnt out the hearth H' is withdrawn and the clinker is allowed to fall into the water pit B'.

A suitable device F' for removing the cooled clinker may be arranged in the bottom of the pit B' as shown, or at one side of the pit or tank.

Where such device is positioned at the bottom of the tank, the whole weight of the clinker would come upon it, and to avoid this a grid-like series of bars G' may be inserted sidewise into or across the pit to support the clinker and take the main weight off the device, so as to permit of its operating more freely, and such bars or grid may be made capable of being rocked if desired. It is to be understood that the water pit B' extends beyond the wall of the combustion zone A' in order that the clinker may be removed by or from the conveyer F' without draining the water from the water pit.

The clinker removed from the pit or tank may be handled in any way desired and being wet no trouble occurs from dust rising or blowing about.

An overflow or spillway J' may also be provided at one side of the pit or tank for the escape of any splash or wave formed when the clinker is dropped into the water. Any suitable device may be employed to maintain the water in the pit at a constant level. A ventilator K' may also be provided for the escape of steam or gas, with a valve or damper k' adapted to close the ventilator when not in use.

Fig. 2 shows an arrangement in which the water pit or tank is extended to the back of the furnace. In this case the pit or tank B² is constructed below the combustion zone A² with an inclined wall b² down which the clinker is adapted to be drawn by gravity, when it is dropped from the hearth, into the tank extension L² in the bottom of which is arranged a clinker-removing device F². The tank extension L² may be closed and provided with a ventilator K² as shown. In the arrangement shown in this figure the hearth H² is formed with openings or per-

forations therethrough and air enters above the tank from an air duct C² and passes to the combustion zone A² through the hearth.

Fig. 3 shows an arrangement very similar to that of Fig. 2 in which the tank extension L³ is made wider and adapted to receive a grab M³ in lieu of the device or conveyor F² shown in the latter figure for the removal of the granulated clinker. This 10 grab may also be employed for feeding the refuse to the furnace.

Fig. 4 shows an arrangement in which the hearth H⁴ is held up by a hydraulic plunger h⁴ adapted when the charge is burnt out 15 to lower the hearth into the tank B⁴. A second horizontally arranged plunger N⁴ may be provided to push the clinker off the hearth, when in the lowered position, into the tank extension b⁴. The advantage of 20 this arrangement is that no splash or wave is formed as the clinker is lowered into the tank.

Or with a similar arrangement of tank, a sliding hearth may be employed which 25 when moved to one side allows the clinker to drop on to the shelf in the tank from which it is pushed into the tank extension by a plunger such as N⁴.

Fig. 5 shows an arrangement in which 30 the hearth H⁵ is hinged as a whole at one side and is allowed to drop or turn on its hinge to lower the clinker into the pit B⁵ which may be constructed as shown in this 35 figure or in any of the other figures of the drawings.

Fig. 6 shows another arrangement in which the hearth H⁶ is supported by a hydraulic plunger h⁶ but in this case the hearth is pivoted on the top of the plunger and a 40 stop O⁶ is provided adapted to tilt the hearth as the ram is lowered to slide the clinker off into the tank B⁶.

In all the arrangements shown, it is obvious that instead of water being maintained 45 continually in the water pit or tank B, the clinker may be first dropped into the tank and water may then be flooded into it to quench the clinker, being afterward pumped out again. Such an arrangement absorbs 50 considerable power for pumping but obviates any splashing or waves when the clinker is dropped into the tank.

Where an extension tank is used and the water is maintained continuously in the 55 tank, the water preferably rises high enough in the tank to seal the space under the grate and prevent passage of air to or from the outside.

In all the arrangements shown the furnace is arranged to be charged from the top, but it is obvious that the furnace may be arranged to be charged in any manner, either mechanically or by hand, from the top or from the back or front, without 60 de- 65 parting from the invention.

A shelf or the like E', E² as shown as preferably formed at the top of the combustion zone A', A² on to which any unburnt material on the fire may be pushed or raked when the clinker is to be dropped, such material being afterward raked or pushed into the combustion zone to start the next fire. Or such shelf may serve for receiving and storing a fresh charge of refuse, or it may be used for both purposes. 75

Furnaces of the type above described may be arranged as individual furnaces or in groups with either or both a common flame chamber and a common clinker tank.

Having thus described the said invention 80 and the best means I know of carrying the same into practical effect, I claim:—

1. In a refuse destructor, the combination of a main chamber, a combustion compartment within the same having substantially 85 vertical walls and of substantially uniform horizontal area, a pit located below the combustion compartment extending beyond the main chamber and communicating with the outer atmosphere, said pit adapted to contain water to form a water seal between the inside and outside of the main chamber, and means including a movable hearth adapted normally to close the bottom of said compartment whereby clinker accumulated in the 90 combustion compartment may be intermittently released and deposited in one mass into said pit and thereby be quenched.

2. In a refuse destructor, the combination of a main chamber, a combustion compartment within the same having substantially 100 vertical walls and of substantially uniform horizontal area, a pit located below the combustion compartment, extending beyond the main chamber and communicating with the outer atmosphere, said pit adapted to contain water to form a water seal between the inside and outside of the main chamber, and means including a movable hearth adapted normally to close the bottom of said compartment whereby clinker accumulated in the 105 combustion compartment may be intermittently released and deposited in one mass into said pit and thereby be quenched, said means comprising a displaceable hearth located below the combustion compartment and above the pit. 110

3. In a refuse destructor, the combination of a main chamber, a combustion compartment within the same having substantially 115 vertical walls and of substantially uniform horizontal area, a pit located below the combustion compartment, extending beyond the main chamber and communicating with the outer atmosphere, said pit adapted to contain water to form a water seal between the inside and outside of the main chamber, means including a movable hearth adapted normally to close the bottom of said compartment whereby clinker accumulated in 120 125 130

the combustion compartment may be intermittently released and deposited in one mass into said pit and be thereby quenched, and a mechanical device for removing and transporting clinker deposited in the pit.

4. In a refuse destructor, the combination of a main chamber, a combustion compartment within the same having substantially vertical walls and of substantially uniform horizontal area, a pit located below the combustion compartment, extending beyond the main chamber and communicating with the outer atmosphere, said pit adapted to contain water to form a water seal between the inside and outside of the main chamber, means including a movable hearth adapted normally to close the bottom of said compartment whereby clinker accumulated in the combustion compartment may be intermittently released and deposited in one mass into said pit and be thereby quenched, said means comprising a displaceable hearth located below the combustion compartment and above the pit, and a mechanical device for removing and transporting clinker deposited in the pit.

5. In a refuse destructor, the combination of a main chamber, a combustion compartment within the same, a pit located below the combustion compartment, extending beyond the main chamber and communicating with the outer atmosphere, said pit adapted to contain water to form a water seal between the inside and outside of the main chamber, means whereby clinker accumulated in the combustion compartment may be intermittently released and deposited in one mass into said pit and be thereby quenched, said means consisting of a displaceable hearth located below the combustion compartment and above the pit, a mechanical device for removing and transporting clinker deposited in the pit and means in the pit to partially support the weight of the clinker deposited therein and prevent the clinker stopping the operation of the removing device.

6. In a refuse destructor, the combination of a main chamber, a combustion compartment within the same, a pit located below the combustion compartment, extending beyond the main chamber and communicating with the outer atmosphere, said pit adapted to contain water to form a water seal between the inside and outside of the main chamber, means whereby clinker accumulated in the combustion compartment may be intermittently released and deposited in one mass into said pit and be thereby quenched, said means consisting of a displaceable hearth located below the combustion compartment and above the pit, a mechanical device for removing and transporting clinker deposited in the pit and means in the pit to partially support the weight of the clinker deposited therein and prevent the clinker stopping the operation of the removing device.

In testimony whereof I have signed my name to this specification in the presence of two subscribing witnesses.

HENRY NORMAN LEASK.
